Primary Examiner — Mehri F Bajoul

(74) *Attorney, Agent, or Firm* — Kaplan Breyer Schwarz, LLP

(57) **CLAIM**

The ornamental design for the ball target, as shown and described.

DESCRIPTION

FIG. 1 is an isometric view of a ball target showing my new design;

FIG. 2 is a front elevation view of the ball target of FIG. 1; FIG. 3 is a rear elevation view of the ball target of FIG. 1; FIG. 4 is a left side elevation view of the ball target of FIG. 1;

FIG. 5 is a right side elevation view of the ball target of FIG. 1; FIG. 6 is a top, plan view of the ball target of FIG. 1; and, FIG. 7 is a bottom, plan view of the ball target of FIG. 1. The features shown in broken lines in the drawing depict portions of the design that form no part of the claimed design.

1 Claim, 5 Drawing Sheets
